UNITED STATES PATENT OFFICE

144,510

DESIGN FOR A LADY'S BAG

Cipriano S. Menor, Lathrop, Calif.

Application February 19, 1945, Serial No. 118,019

Term of patent 14 years

(Cl. D87—3)

To all whom it may concern:

Be it known that I, Cipriano S. Menor, a national of the United States, residing at Lathrop, in the county of San Joaquin and State of California, have invented a new, original, and ornamental Design for Lady's Bag, of which the following is a specification, reference being had to the accompanying drawing, forming a part thereof.

looking at one side and showing my new design; the opposite side of the bag presenting the same appearance.

Figure 2 is a perspective view of the lady's bag as open, and looking into the interior thereof.

I claim:

The ornamental design for a lady's bag, as shown and described.

CIPRIANO S. MENOR.
